CHARLES WAINWRIGHT, OF ERIE, PENNSYLVANIA.

INTAKE-UNLOADER FOR COMPRESSOR SERVICE.

1,324,705.

Specification of Letters Patent.

Patented Dec. 9, 1919.

Application filed May 17, 1919. Serial No. 297,828.

To all whom it may concern:

Be it known that I, CHARLES WAINWRIGHT, a citizen of the United States, residing at Erie, in the county of Erie and 5 State of Pennsylvania, have invented new and useful Improvements in Intake-Unloaders for Compressor Service, of which the following is a specification.

The general object of my present invention is the provision of means for equalizing the pressure on the driving piston and the chamber leading to the intake valve or valves of the compressor cylinder when the intake unloader is on the point of opening 15 to let atmospheric pressure into the intake chamber of the compressor cylinder.

To the attainment of the foregoing the invention consists in the peculiar and advantageous intake unloader, hereinafter described and definitely claimed.

In the accompanying drawings, hereby made a part hereof:

Figure 1 is a sectional view of the intake unloader constituting the best practical embodiment of my invention of which I am cognizant.

Fig. 2 is a detail perspective of the piston complementary to the automatic means for controlling the relation of pressure between 30 the chambers K and L of the unloader.

Similar letters of reference designate corresponding parts in both views of the drawings.

By particular reference to Fig. 1, it will 35 be observed that the unloader casing contains chambers S and K, the chamber S being designed to be connected at A with the atmosphere or with any other source of supply to the compressor, and the chamber 40 K being adapted to be attached at B to the intake of a compressor cylinder. Intermediate the chambers S and K is a partition A' in which is a port A² surrounded by a valve seat A³. The arrows in Fig. 1 indicate the direction of travel of the air. The 45 intake unloader consists of a driving piston C, a piston rod E, a plate or body D, a spring F and a rod F' bearing an abutment F² for the spring F and disposed in a bearing G which also affords an opposite abutment for the spring and a valve casing N. At H is a standard regulator for operating and controlling the piston C by coöperation with the automatic means J for controlling 55 the relation of pressure between the chamber K and the chamber L at the opposite

side of the piston C with reference to the chamber S. The regulator H includes a piston O, a regulating spring P, and a screw Q for adjusting the tension of said spring. 60 A pipe M leads to the chamber of the regulator H at the inner side of the piston O, and intermediate the said chamber and the chamber L, is a duct R. At W is a minute vent in communication with the chamber 65 L, and at X is a conduit intermediate of the chamber K and the interior of the casing of the automatic means J. In the said casing of the means J is a piston T together with an additional piston portion T' and a 70 spring Z.

In applying my improvement, the pipe M is connected to the air receiver to which the compressor may be attached, and in the operation of the unloader, the piston O of the 75 regulator H rises against the tension of the spring P coincident with the raising of the pressure to the predetermined point. This permits air or other fluid under pressure to pass through the duct R into the chamber L, 80 whereupon the pressure first forces the piston T against its seat U, with the result that connection between the chambers L and K is cut off or interrupted. Secondly, the pressure alluded to forces the piston C downwardly until the valve plate body D bears 85 upon its seat A³. From this it follows that the connection between the source of supply and the intake of the compressor cylinder is cut off. Following a predetermined drop of 90 pressure, the compressed air in the chamber L escapes through the vent W, and then when the pressure is almost reduced to atmospheric pressure in the chamber L, the piston T is moved away from its seat U by the expansion of the spring Z. This is brought 95 about by the employment of the piston T' fixed with respect to the piston T. In consequence communication is re-established between the chambers K and L; also, the 100 spring F is only called upon to overcome the friction of the piston C and the weight thereof, in order to force the valve plate body D away from the seat A³. The stem of the pistons T T' fits loosely in the casing 105 to afford atmospheric pressure above the piston T'.

It will be apparent from the foregoing that I have provided an intake unloader in which a very light spring may be used, and one in which when closed the valve plate body D is held lightly against its seat, and

in which when on the point of opening there is no vacuum calculated to hold the valve plate body D to the seat A³. This latter is due to the fact that the automatic means J 5 equalizes the pressure in the chambers K and L and neutralizes the atmospheric pressure imposed on the valve plate body D. From this it follows that not only is it feasible to employ a very light spring F, but at the 10 same time the shock and strain imposed upon the compressor with an intake unloader of the ordinary type, is eliminated.

Having described my invention, what I claim and desire to secure by Letters-Pat- 15 ent, is:

1. An intake unloader including a regulator and means for equalizing the pressure in the intake chamber of a compressor cylinder and on the driving piston of the un- 20 loader when the regulator of the unloader interrupts the supply of fluid under pressure to said driving piston.
2. An intake unloader including a regulator and comprising means for equalizing 25 the pressure at the outlet side of the un-

loader casing and on the driving piston of the unloader when the regulator of the un- loader cuts off communication of compressed air to said driving piston.

3. In an intake unloader including a regu- 30 lator, the combination of a driving piston, means for equalizing the pressure at the outlet side of the unloader casing and on said driving piston when the regulator of the intake unloader cuts off communication of 35 compressed air to said driving piston.

4. An intake unloader comprising a cas- 40 ing in which are chambers direct commu- nication between which is controlled by a driving piston, the said driving piston, a regulator in communication with an addi- 45 tional chamber in the casing, and means in- termediate said additional chamber and one of the first-named chambers for equalizing the pressure at the outlet side of the un- loader casing and on the driving piston when the regulator cuts off communication of compressed air to the driving piston.

In testimony whereof I affix my signature.
CHARLES WAINWRIGHT.
